DISPOSAL DEVICE

Oakley V. Harman, Holden, W. Va.

Application July 18, 1952, Serial No. 299,722

2 Claims. (Cl. 232—43.2)

1

This invention relates to improvements in waste and trash disposal devices, and the primary object of the invention is to provide a more efficient device of this kind which is highly adaptable to being made either in the form of an independent, attractive and serviceable article of furniture for home or office or as a unit for incorporation into other articles of furniture of the types used in homes, offices, and workshops, and may be constructed of wood or of light metal to match the type of office or home furniture with which it may be associated.

Other important objects and advantageous features of the invention will be apparent from the following description and the accompanying drawings, wherein, for purposes of illustration only, a specific embodiment of the invention is set forth in detail.

In the drawings:

Figure 1 is a front perspective view with the drawer in open position;

Figure 2 is a bottom perspective view of the drawer;

Figure 3 is a transverse vertical section taken on the line 3—3 of Figure 1;

Figure 4 is a transverse vertical section taken on the line 4—4 of Figure 3;

Figure 5 is a view similar to Figure 3, showing the drawer in closed position with the bottom panel in depressed dumping position; and

Figure 6 is a transverse vertical section taken on the line 6—6 of Figure 5.

Referring in detail to the drawings, wherein like numerals designate like parts throughout the several views, the illustrated disposal device comprises a cabinet 9 of generally rectangular form, comprising a full-height back wall 10, full-height side walls 11, 11, a top 12 resting upon and secured to the upper ends of the back and side walls. The side walls 11 have their lower front corners notched or undercut, as indicated at 13, and a cleat 14 extends between and is butted to the vertical edges 15 of the notches 13. A bottom 16 extends forwardly from the back wall 10 and between the side walls 11, 11 at the level of the top of the cleat 14 and is secured to all three.

An apertured front wall 18 abuts the forward edge 19 of the bottom 16 and is connected to the front edges of the side walls 11, 11 and reaches to the under side of the top 12. A door 20 is hinged at one side, as indicated at 21, in a door opening 22 formed in the lower part of the front wall 18 and extending through the lower edge of the front wall 18, and is provided with a knob 23.

A shallower drawer opening 24 is formed in the

front wall 18 and is slightly vertically spaced from both the top 12 and the upper edge 25 of the door opening 22.

Slidably resting upon the cabinet bottom 16 is a preferably rectangular trash or waste receptacle 26 having a handle 27 on its forward end. The receptacle 26 is preferably of less height than the door opening 22 and only slightly narrower than the inside dimensions of the cabinet so that the receptacle will have maximum capacity and at the same time be easily removed and replaced through the door opening 22. If desired, the receptacle 26 can be replaced by a waste basket (not shown) or by a completely disposable card board container so as to render the unit more sanitary and provide greater ease in disposing of waste matter deposited in the unit. Blocks 28 on the bottom 16 space the opposite sides of the receptacle 26 from the cabinet side-walls so as to hold the receptacle in registry with the door opening 22 and to reduce frictional contact of the sides of the receptacle with the cabinet side-walls 11, 11 in removing and replacing the receptacle 26.

25 An upper pair of horizontal blocks 30, 30 extend downwardly from the top along the cabinet side walls 11, 11 to a level slightly below the upper edge 29 of the drawer opening 24, and a lower pair of horizontal blocks 31, 31 extend along the side walls 11, 11 and are spaced below the blocks 30, 30, the blocks 30, 30 and 31, 31 preferably extending the full depth of the cabinet 9. The upper blocks 30 have laterally inwardly projecting horizontal guides 32 whose under sides slidably engage the top of the drawer hereinafter described, and the lower blocks 31 have laterally inwardly projecting guides 33 upon which the bottom of the said drawer slidably rests.

The guides 33 are connected at their forward ends by a horizontal cross-piece 34 and have abbreviated portions 35 of increased width adjacent to the cross-piece 34, which have rearwardly and downwardly curved upper surfaces 36 which serve as elevating or levelling cams, in a manner hereinafter described.

The dumping drawer, generally designated 38, is of a cross section preferably forming a sliding fit in the drawer opening 24, and of a length to reach the cabinet back wall 10 in the closed position of the drawer with the front of the drawer preferably flush with the front wall 18 of the cabinet. The drawer 38 comprises a front wall 39, opposed side walls 40, 40 secured flush with the ends of the front wall 39, and a back wall 41 secured to the rear ends of the side walls 40.

The back wall 41 has thereon a forwardly declining plate 42 which serves to convey away from the back wall 41 any waste or trash placed in the drawer.

The drawer 38 further comprises an abbreviated bottom wall 43 extending rearwardly a short distance from the front wall 39 and terminating in a rear free edge 44. The bottom wall 43 is only about one-third of the length of the drawer 38. On the rear free edge 44 is secured a leaf 45 of a hinge 46 having a hinge pin 47 at or above the top of the bottom wall 43, and another hinge leaf 48 pivoted on the hinge pin. The hinge 46 may be either two hinge leaves, one on each side or one very long hinge leaf of the full width of the panel.

The hinge 46 serves as a hinge mounting for the tiltable dumping panel 50. The panel 50 is slightly narrower than the distance between the drawer side walls 40, 40 and is of a length, approximating two-thirds of the length of the drawer 38, such that in the closed horizontal position of the panel, its forward end 51 will be close to or engaged with the front wall 39 of the drawer and the rear end 52 of the panel 50 will be close to and forwardly spaced from the depressed end 53 of the declining back wall plate. The hinge leaf 48 is secured to the under side of the tilting panel 50 at a point forwardly of the middle or center of gravity of the panel 50, so that the panel 50 will tilt rearwardly and downwardly whenever free to do so. At the opposite sides of the panel 50 near its rear end 52 there are secured to the under side of the panel 50, elevating or levelling cams 54, similar to but reversed with respect to the cams 35. The cams 54 act also as weights for helping the downward gravitational swing of the panel.

It will be apparent from the foregoing and the drawings that in the inward or closed position of the drawer 38, the cams 54 are unsupported by the cams 35 or by the guides 33, so that the drawer 38 necessarily occupies a declining dumping position, as shown in Figures 5 and 6. As the drawer 38 is pulled open from a closed position, the tilting panel cams 54 ride up on the guide cams 35 so that the panel 50 is elevated to horizontal position, with its forward part resting upon the drawer bottom 43 and with its cams 54 resting upon the guides 33, as shown in Figures 3 and 4. The drawer 38 being in open position, and trash or waste having been deposited in the drawer, disposal of the waste or trash into the receptacle 26 is accomplished simply by pushing in the drawer 38 to its closed position, since this operation produces downward tilting of the panel so that its burden or waste or trash slides thereon gravitationally into the receptacle 26. The cams 54, in units constructed of metal, can be roller bearings, and the guides 33 can be bearings or bearing channels, which add to the ease of operation.

It will be observed that the simple rectangular form of the cabinet 9 and the arrangement and manner of operation of the drawer 38 and of the receptacle 26 permits of ready incorporation of the device into kitchen, office, and workshop cabinet structures, wherein the device is as inconspicuous as other units of such structures.

What is claimed is:

1. In a disposal device, a cabinet having spaced side walls and a front wall and a bottom wall extending between the side walls at a level below the upper ends of the side walls and front wall, said front wall being formed with a drawer open-

ing spaced upwardly from said bottom wall, a pair of horizontal guides mounted on the inner sides of the cabinet side walls having upper surfaces on a level with the lower side of the drawer opening, said guides having cam portions projecting laterally inwardly from said side walls, said cam portions having rear ends forwardly spaced from the cabinet back wall, said rear ends having rearwardly and downwardly declining cam surfaces, a drawer movable through said drawer opening on said guides from a pushed-in closed position to a pulled-out open position relative to the cabinet, said drawer having an abbreviated bottom wall extending rearwardly from the front end of the drawer, said abbreviated bottom wall having a free rear end spaced forwardly from the rear end of the drawer, a dumping panel, pivot means pivoting the panel at a point intermediate its ends on the free rear end of the abbreviated bottom wall with the dumping panel extending forwardly and rearwardly relative to said free rear end, the pivotal axis of said pivot means being horizontal and extending crosswise of the drawer and being positioned forwardly of the center of gravity of the dumping panel so that the dumping panel is forced by gravity to swing downwardly and rearwardly when free to do so, and cam portions on the under side of said dumping panel at the rear end thereof having upwardly and forwardly inclined cam surfaces arranged to ride up on the cam surfaces of the guide cam portions as the drawer is moved from a closed position to an open position whereby the dumping panel is tilted upwardly to a horizontal position in which its cam portions rest upon said horizontal guides and the drawer is conditioned to receive waste, subsequent inward pushing of the drawer to closed position serving to cause the dumping panel cam portions to disengage from the guide cam portions and enable the dumping panel to pivot gravitationally to a rearwardly declining position wherein the waste slides gravitationally from the dumping panel into a receptacle on the cabinet bottom wall.

2. In a disposal device, a cabinet having spaced side walls and a front wall and a bottom wall extending between the side walls at a level below the upper ends of the side walls and front wall, said front wall being formed with a drawer opening spaced upwardly from said bottom wall, a pair of horizontal guides mounted on the inner sides of the cabinet side walls having upper surfaces on a level with the lower side of the drawer opening, said guides having cam portions projecting laterally inwardly from said side walls, said cam portions having rear ends forwardly spaced from the cabinet back wall, said rear ends having rearwardly and downwardly declining cam surfaces, a drawer movable through said drawer opening on said guides from a pushed-in closed position to a pulled-out open position relative to the cabinet, said drawer having an abbreviated bottom wall extending rearwardly from the front end of the drawer, said abbreviated bottom wall having a free rear end spaced forwardly from the rear end of the drawer, a dumping panel, pivot means pivoting the panel at a point intermediate its ends on the free rear end of the abbreviated bottom wall with the dumping panel extending forwardly and rearwardly relative to said free rear end, the pivotal axis of said pivot means being horizontal and extending crosswise of the drawer and being positioned forwardly of the center of gravity of the dump-

ing panel so that the dumping panel is forced by gravity to swing downwardly and rearwardly when free so do so, and cam portions on the under side of said dumping panel at the rear end thereof having upwardly and forwardly inclined cam surfaces arranged to ride up on the cam surfaces of the guide cam portions as the drawer is moved from a closed position to an open position whereby the dumping panel is tilted upwardly to a horizontal position in which its cam portions rest upon said horizontal guides and the drawer is conditioned to receive waste, subsequent inward pushing of the drawer to closed position serving to cause the dumping panel cam portions to disengage from the guide cam portions and enable the dumping panel to pivot gravitationally to a rearwardly declining position wherein the

waste slides gravitationally from the dumping panel into a receptacle on the cabinet bottom wall, said drawer having a rear wall, and a forwardly declining plate on said rear wall serving to move waste forwardly away from the drawer rear wall onto the dumping panel.
